UNITED STATES PATENT OFFICE.

CHARLES C. SPENGLER, OF ROCKFORD, ILLINOIS.

LOCKING DEVICE FOR CASH-REGISTERS.

SPECIFICATION forming part of Letters Patent No. 766,070, dated July 26, 1904.

Application filed October 12, 1903. Serial No. 176,757. (No model.)

To all whom it may concern:

Be it known that I, CHARLES C. SPENGLER, a citizen of the United States, residing at Rockford, in the county of Winnebago and State 5 of Illinois, have invented certain new and useful Improvements in Locking Devices for Cash-Registers, of which the following is a specification.

The object of this invention is the production of a locking device to prevent the accidental or improper actuation of the registering mechanism of a cash-register.

In the accompanying drawings, Figure 1 is a transverse vertical sectional view taken on dotted line 1 1, Fig. 4, through a cash-register embodying the features of this invention. Fig. 2 is a similar view in detail showing the positions assumed by the locking device when one of the keys of the register is slightly depressed. Fig. 3 is a view similar to the foregoing figure, showing the positions of the parts of the mechanism when one of the keys is fully depressed. Fig. 4 is a detail front elevation of a cash-register, showing the application thereto of the locking device of this invention.

In a cash-register embodying the features of this invention, A refers to the supporting-framework; A', to one of the actuating-keys; 30 A², to a shaft upon which all the actuating-keys are loosely mounted, and A³ to a rock-bar with which by means of the link A⁴ and the rigid arm A⁵ the key A' is connected.

A⁶ is a restoring rock-bar for all of the 35 keys and for the coin-slides A⁷, with which coin-slides the rock-bars A³ and A⁶ are connected by means of the pins A⁸ and A⁹, respectively.

A¹⁰ is a spring, one end of which is attached 40 to a rigid support upon the supporting-frame A, the other end to an arm A¹¹, extending from the side of the rock-bar A⁶. The restoring rock-bar A⁶ is provided with an arm A¹², the purpose of which will appear hereinafter. 45 B refers to the counter-shaft, upon which is supported the counter mechanism (not shown) of the cash-register.

B' refers to an oscillatory shaft for rotating said counter-shaft; B², to a pinion loosely 50 mounted on the counter-shaft; B³, to a toothed

sector fixed on said oscillatory shaft B' and meshing with said pinion B²; B⁴, to a spring-actuated pawl carried by said pinion and adapted to engage with the teeth in the face of a ratchet-wheel B⁵, which ratchet-wheel is 55 fixed on the counter-shaft B and receives motion from the pawl B⁴ to rotate said counter-shaft, and B⁶ refers to a restoring coil-spring carried by an arm B⁷, fixed upon a stationary rod B⁸, which spring is connected at its lower 60 end with a pin B⁹, extending from the oscillatory shaft B'.

Motion is communicated from the key A' to the oscillatory shaft B' by means of the spring-cushioned mechanism B¹⁰, the lower 65 end of which mechanism rests upon the rear end of the key A' and the upper end of which contacts with a rod B¹¹, carried by an arm B¹², which arm is fixed with relation to said oscillatory shaft B'. The shaft B' also is provided with an upwardly-extending arm B¹³, at the upper end of which arm is pivotally supported a link B¹⁴, having an adjusting-screw B¹⁵ in its free end.

A ratchet-wheel C is fixed upon the shaft 75 B, the teeth of which ratchet-wheel are adapted to be engaged by two pawls C' and C², pivotally mounted upon the supporting-framework A by means of pivots C⁴ C³. The pawl C' is provided with a pin C⁶, adapted to extend within the link B¹⁴, and is also provided with a flat spring C⁷, fixed to its rear side, which spring is adapted to bear upon the pin C' in the supporting-framework A. The tendency of the spring C⁷ is to withdraw the 85 pawl C' from engagement with the teeth of the ratchet-wheel C. The pawl C² is provided with an opening C⁸ in its rear end for the passage of the releasing-rod, to be next described.

A releasing-rod D is pivotally connected with the oscillatory shaft A⁶ by means of the arm A¹² of said shaft, and said releasing-rod extends upwardly from said arm, near its upper end passing through the opening C⁸ in the 95 pawl C² and being provided with a collar D' below said pawl and with a coil-spring D² and a collar D³ above said pawl. The collars D' and D³ are frictionally mounted upon the releasing-rod D, being held thereon by means 100

of screws passing through flanges D⁴ upon said collars, and therefore are adjustable in position lengthwise of said rod.

A locking-dog E is pivotally mounted upon 5 the supporting-framework A by means of the pin E'. The forward portion of said dog lies in contact with the upper end of the pawl C', occupying such a position with relation to said pawl that the pawl cannot be withdrawn from 10 engagement with the teeth of the ratchet-wheel C until the dog E is oscillated upon its pivot. The rear end of the dog E is curved upwardly and occupies a suitable position to be engaged by the flange D⁴ of the upper collar 15 D³ upon the rod D. In the normal position of the parts, as illustrated in Fig. 1, the pawl C' engages the teeth of the ratchet-wheel C and prevents rotation thereof.

In operation depressing the operating-key 20 A' oscillates the rock-bar A³ by reason of the link (A⁴) and arm (A⁵) connection between said operating-lever and said rock-bar. The coin-slide (A⁷) connection between the rock-bar A³ and the rock-bar A⁶ causes the downward 25 movement of the key A' also to oscillate said rock-bar A⁶, and by the movement of the arm A¹², extending from said rock-bar, the releasing-bar D also is depressed. Motion from the operating-key A' is transmitted, through the 30 spring-cushion device B¹⁰, the rod B¹¹, and the arm B¹², to the oscillatory shaft B', said shaft being moved against the tension of its restoring-spring B⁶. This movement of said oscillatory shaft moves the arm B¹³ and the 35 link B¹⁴, sliding said link longitudinally upon the pin C⁵ of the pawl C'. The first effect of the downward movement of the releasing-bar D is to raise the forward end of the pawl C² into engagement with the teeth of the ratchet- 40 wheel C, which occurs by reason of the pressure of the coil-spring D² bearing upon the rear end of the pawl C².

The further downward movement of the bar D causes the flange D⁴ of the collar D³ to engage the rear end of the dog E, rock said dog upon its pivot E', and withdraw its forward end from engagement with the pawl C'. When the pawl C' is so freed, it is rocked upon its pivot C⁴ by the flat spring C⁶, withdrawing 45 the upper end of said pawl from the teeth of the ratchet-wheel C. As soon as pressure is removed from the operating-key A' the spring A¹⁰ oscillates the rock-bar A⁶ and through the arm A¹² raises the restoring-rod D. As the 50 restoring-rod is moved upward the collar D' on said rod comes into contact with the rear end of the pawl C², rocking said pawl on its pivot and withdrawing its forward end from engagement with the teeth of the ratchet- 55 wheel C. At this instant the oscillatory shaft B' through its gear-sector B³ rotates the pinion B² and its ratchet B⁵. The pawl B⁴ engaging the teeth of the ratchet B⁵ rotates the counter-shaft B. At the end of its oscillatory 60 movement the shaft B' through its arm B¹³

and link B¹⁴ draws the pawl C' into engagement with the teeth of the ratchet-wheel C and the dog E drops by gravity into its locking position behind the upper end of said pawl C'. The effective length of the link B¹⁴ 70 may be changed at will by turning the adjusting-screw B¹⁵. The dog E holds the pawl C' in engagement with the teeth of the ratchet-wheel C at all times, save the instant when the counter-shaft must be rotated in its registry movement. As soon as this registry movement is completed the pawl is drawn into engagement with the teeth of said ratchet-wheel C by means of the link B¹⁴ and is held 75 in engagement with said teeth by means of the dog E.

It is clear that many changes may be resorted to in the construction of this locking device without departing from the spirit and scope of my invention, wherefore I desire to 80 have it understood that I do not limit myself to the embodiment herein shown and described.

I claim as my invention—

1. In a counter-locking device for cash-registers, in combination, a detent adapted to prevent the operation of the counter mechanism; a spring for withdrawing and a link for restoring said detent; a dog for guarding the detent; and means operating with the operation of the 90 register for withdrawing said dog from said detent.

2. In a counter-locking device for cash-registers, in combination, a counter - shaft; a ratchet-wheel rotatable with the counter mechanism; a locking-pawl for said ratchet-wheel; a spring for withdrawing said pawl from said ratchet; a dog for holding said pawl in engagement with said ratchet; and means operating 100 with the operation of the register for withdrawing said dog from engagement with said pawl.

3. In a counter-locking device for cash-registers, in combination, a counter - shaft; a ratchet-wheel rotatable with the counter mechanism; a locking-pawl for said ratchet-wheel; means for holding said pawl in engagement with said ratchet-wheel; means for withdrawing said pawl from said ratchet-wheel; a dog for guarding said pawl; and means operating 110 with the operation of the register for withdrawing said dog from engagement with said ratchet.

4. In a counter-locking device for cash-registers, in combination, a counter - shaft; a ratchet-wheel rotatable with the counter mechanism; a locking-pawl for said ratchet-wheel; means for holding said pawl in engagement with said ratchet-wheel; means for withdrawing said pawl from said ratchet-wheel; a dog for guarding said pawl; and a releasing-rod adapted to withdraw said dog from engagement with said pawl.

5. In a counter-locking device for cash-registers, in combination, a counter - shaft; a 120

ratchet-wheel rotatable with the counter mechanism; a locking-pawl for said ratchet-wheel; a spring for withdrawing said pawl from engagement with the teeth of said ratchet-wheel; 5 mechanism for normally holding said pawl in engagement with the teeth of said ratchet-wheel; a dog for guarding said pawl; and a releasing-rod adapted to move said dog from

engagement with said pawl during the operation of the register mechanism.
